(57) **CLAIM**

I claim the ornamental design for a urinal, as shown and described.

DESCRIPTION

FIG. 1 is a perspective view of a urinal, showing my new design;

FIG. 2 is a front view thereof;

FIG. 3 is a side view thereof;

FIG. 4 is another side view thereof; and,

FIG. 5 is a top view thereof.

The broken lines in the drawings depict portions of the urinal that form no part of the claimed design.

1 Claim, 5 Drawing Sheets
